GAS-TURBINE.

No. 887,627.

Specification of Letters Patent.

Patented May 12, 1908.

Application filed February 27, 1906. Serial No. 303,237.

To all whom it may concern:

Be it known that I, LEWIS A. HAINES, a citizen of the United States, residing at Mount Vernon, in the county of Knox and State of Ohio, have invented new and useful Improvements in Gas-Turbines, of which the following is a specification.

This invention relates to a gas turbine, and the primary object of the same is to equalize the end thrust of the turbine shaft by locating the turbine between two feeding or pressure chambers for receiving the energy of the ignited gas, and also by locating the exhaust chamber between the turbines to commonly receive the pressure medium after it has fully completed its work with respect to the turbines.

A further object of the invention is to prevent any of the ignited charges from returning into the pump cylinders and prevent the gas from the mixing chambers from flowing freely into the pumps and to reduce the friction of the pumps to a minimum.

A further object of the invention is to fully inclose or incase the working parts, passages, and chambers with a cooling medium or water jacket means in which a thorough circulation of water is maintained, with obvious advantages in the structural durability of the turbine as a whole and increased efficiency in the operation of the several movable parts.

A still further object of the invention is to simplify the organization of gas turbines or motors, and increase the power thereof within minimized proportions and reduce the expense of maintenance, render the several parts practically noiseless in their operation, and embody in a complete motor structure a duplex organization practically similar in construction in all its details and whereby corresponding pumps of the two sets on opposite sides of the turbine on the same side of the shaft and in the same axial plane operate in alternation to compress power fluid and set up a power generating operation with respect to the turbine shaft such that the latter will have an unimpeded or regular rotation.

In its broadest sense, the invention embodies a plurality of pump devices having means for supplying gas thereto; a feeding chamber, ignition chambers between the feeding chamber and pump devices, and having communication with both of the latter, a turbine, and automatically operating means

in the ignition chambers for admitting the charge of gas to the latter from the pump devices, shutting off communication with the pump devices, and opening communication between the mixing chamber and the receiving chamber after explosion of the charge in the said ignition chamber. The gas is admitted from the pumps or pump devices into the ignition chambers when the feeding chamber is shut off, and communication between the ignition chambers and pumps is shut off just prior to the explosion in the said ignition chambers and the receiving chamber opened to the ignition chamber subsequent to such explosion, so that when the turbine receives or is actuated by the exploded gas energy or pressure medium in the feeding chamber, the pumps and ignition chambers are completely cut off from the said feeding chamber. The pumps draw their supply from the mixing chamber and the latter is shut out from the pump cylinders just prior to the operation of forcing the charge of gas into the ignition chambers, and when the explosion takes place in the latter chambers the pumps are cut out from communication therewith as well as the feeding chamber, the said feeding chamber being afterward opened up to the ignition chamber, and during a time when the pumps are still cut off from communication with the ignition chambers.

In the drawings, Figure 1 is a side elevation of a turbine or motor embodying the features of the invention and showing a portion of the casing removed. Fig. 2 is a longitudinal vertical section of the same. Fig. 3 is an end elevation. Fig. 4 is a section on the line 4—4—, Fig. 1. Fig. 5 is a detail view of one of the cams for actuating the valve mechanism in the ignition chamber. Fig. 6 is a detail sectional view, particularly showing the discharge valve and bushing in detail. Fig. 7 is a plan view of the bottom of one of the cylinder heads. Fig. 8 is a top plan view of one of the pump cylinders. Fig. 9 is a detail elevation of one of the feeding chambers.

Similar characters of reference are employed to indicate corresponding parts in the several views.

The numeral 1 designates a suitable shaft, from which motion may be transmitted to any suitable mechanism desired to be driven or actuated by the improved turbine or motor. The turbine or motor is of duplex construction, or has operating with the shaft 1

two sets of pumps, mixing chambers, ignition chambers, receiving chambers, and two turbines, and in the following description one set of pumps and relatively coöperating devices, as at A, will be particularly referred to solely, as they are in every respect similar to the remaining set of pumps and coöperating devices B. The corresponding pumps of the two sets on opposite sides of the turbine on the same side of the shaft and in the same axial plane operate in alternation to compress power fluid to give the shaft 1 a regular or steady rotary movement.

Referring more particularly to Fig. 4, which is a transverse vertical section through the set A of the pump devices and coöperating elements, a cylinder frame 2 is shown for giving support and proper assemblage to a plurality of cylinders 3 arranged in radial relation in the said frame and having heads 4. Within the cylinders are pistons 5 suitably packed and formed with central recesses 6 opening through the inner ends thereof.

Movably attached to the pistons 5 within the recesses 6 are the outer ends of connecting rods 7, one of said rods, as at 7^a, having a particular construction and function differing from the remaining rods, which will be presently stated. The inner ends of the connecting rods 7 are movably attached to an eccentric strap 8, which is arranged in coöperative relation to an eccentric 9 secured on the shaft 1. The inner end of the connecting rod 7^a is fixed to the eccentric strap 8, as at 10, and serves as a supporting leg as well as a reciprocating connecting rod, and its particular function is to maintain the eccentric strap in proper operative relation with respect to the connecting rods 7, which are movably attached at their inner ends to said strap. The utilization of the connecting rod 7^a as a supporting leg is an essential detail feature of construction, not only by reason of the fact that it performs a double service, but materially minimizes the contributory elements of the motor organization in dispensing with additional features to hold the eccentric strap in proper position and to maintain a regularity of movement thereof. As shown in the accompanying drawings, six pumps are employed for indrawing or feeding the gas to the motor, but this number may be modified, and furthermore, instead of employing an eccentric strap to actuate the connecting rods 7 and pistons 5, the well known equivalent therefor consisting of a crank shaft might be substituted, without in the least modifying the essential features of construction or the operation of the pump devices.

The construction of each cylinder 3 and its head 4 is clearly shown by Figs. 2, 7, and 8, and embodies a bore 11 for the piston 5 thereof, a bore 12 for the valve mechanism or device coöperating with the ignition cham-

ber, and elongated water inlets 13 for the cylinder heads. The heads 4 are each formed with a projection 14 over which the lower end of the cylinder 3 is fitted, a continuation of the bore 12 in the body of the cylinder, as at 15, and water inlets 16. The body of each cylinder is surrounded by a cooling or water receiving chamber or cavity, as at 17, Fig. 8, and shown by dotted lines, and the head 4 has a water space 18 in communication with the inlets 16. In the center of the projection 14 a valve seat 19 is formed to receive a valve 20, having an outwardly extending stem 21, projecting into a cap 22, which contains a spring 23 surrounding the said stem and operating to draw or close the valve 20 against the seat 19.

Extending outwardly through the side portion of the head is a gas inlet port 24, which has communication with an annular mixing chamber 25 surrounding the end of the motor or turbine, and has a gas supply pipe 26 communicating therewith and running from any suitable source or supply. This pipe 26 branches in opposite directions and connects with the mixing chambers at opposite ends of the motor or turbine, and at its intermediate portion a suitable controlling valve 27 will be located to regulate the supply of gas in accordance with the speed of the motor and with which may be used any suitable form of governor, so as to avoid dissipation of the energy or excessive feed at times when the motor does not require a rapid supply, or when, by continued operation, there may be stored in the turbine feeding chambers, which will be more fully hereinafter explained, enough pressure to maintain the requisite or normal speed of the turbine. Each head 4 also has a gas outlet port 28 communicating with the cylinder, including in its organization the said head at one side of the center or of the position of the valve 20, the said port 28 also leading into an ignition chamber 29 formed in part and mainly by the cylinder and head construction just explained and provided with a surrounding casing 30, adapted to have electric spark plugs, diagrammatically shown at 31, and which may be of any preferred form to ignite the gas after compression in the ignition chamber. The ignition chambers are similar in number to the pump devices and have communication with the latter. Within each ignition chamber and coöperating with each pump device, is a combined controlling valve and compression piston operated by the shaft 1 through the medium of a cam 32, shown in detail by Fig. 5, and having such transverse contour as to render the operation of the combined piston and valve mechanism in the ignition chamber positive and reliable. This combined valve and compression or piston mechanism is clearly illustrated in detail by Fig. 6, and in

cludes a valve stem plunger 33, having an inner bifurcated or slotted end 34 in which is disposed a roller 35, the bifurcated or slotted end 34 embracing the cam 32. On the outer 5 end of the plunger 33 a combined valve and compression piston 36 is secured and has inlet and outlet ports 37 and 38 located in opposite portions thereof, the port 37 being adapted to coincide with the outlet port 28 10 in the head 4 of the adjacent pump cylinder. A suitable casing 39 surrounds this combined valve piston mechanism, and fitted in the inner extremity of said casing is a bushing 40, for holding a spring 41, which engages a 15 shouldered portion 42 of the valve stem plunger 33 and the inner head 43. This spring 41 operates to throw the valve stem plunger 33 inwardly to preserve a proper coöperation thereof with the cam 32, and the latter, by 20 its construction, which will be presently specifically described, forces the combined valve and piston 36 outwardly under certain conditions and at proper times.

Surrounding the motor close to the ignition chambers and in communication with the latter, is a feeding chamber 44, which may also be properly termed a pressure chamber, one of these pressure chambers being used with each set of pump devices A and 30 B and the coöperating parts just explained in connection with the set of pump devices A. The form of this feeding or pressure chamber is illustrated in detail by Fig. 9, and has, at 35 intervals, a plurality of inlet ports 45, in communication with the discharge ports of the ignition and compression chambers 29 and adapted to be placed in communication with the latter through the medium of the port 38 of the combined valve and piston 36. 40 It will be observed from Fig. 2, that the inlet port 45 and discharge port communicating therewith and leading to the ignition chamber are located a greater distance from the center of the turbine than the discharge 45 port 28 in the head of the pump cylinder, and which establishes communication between the said cylinder and the ignition chamber. This disposition of the ports, as just specified, is to accomplish a communication between 50 the pump cylinder and the ignition chambers and between the feeding or pressure chamber 44 and the latter chambers at different intervals. The inner side or portion of the feeding chamber 44 has suitable outlet 55 ports or egress openings 46, disposed at angles to the blades or buckets of a turbine 47 secured to the shaft 1 and having close position with respect to the said feeding or pressure chamber 44. Each of the turbines, there 60 being two, as shown, is composed of stages, as will be readily understood, the central stage being fixed in the shell 48, and the outer stages revolving around said center stage so that the pressure first strikes the 65 revolving blades or buckets and then impacts

against the stationary blades or buckets fixed in the casing, and from the latter blades or buckets it is guided to the next revolving stage of blades or buckets. The blades or buckets of the several turbine stages will be 70 so shaped and disposed as to be effective in setting up a rotary movement of the shaft 1 through the hub of the turbine. There may be as many stages used in each turbine as the pressure may require, so as to use all the 75 energy of gas before it reaches the exhaust chamber 49, which is located between the two turbines, and the latter are held in opposing positions at the center of the motor, as clearly shown in the drawings, and particularly by Fig. 1, wherein a part of the turbine shell is removed. From the centrally located exhaust chamber the gas may be conducted by any suitable means from the outlet 50, and as all the energy or pressure of 80 the gas, after reaching the exhaust chamber 49, will have been utilized, there will be no noise attending the discharge of the exhaust gas. Surrounding the feeding or pressure chamber 44 are water spaces 51, and the turbine shell or inclosure also includes a water jacket 52, both the water spaces 51 and 52 and all the water spaces heretofore described being in communication through the medium of supply inlets in one part with respect to 85 the other.

At this point attention is called to Fig. 4 which clearly shows water pockets 53 between the cylinders 3 and having communication with the inside of the pump frames 100 through the medium of inlets 54 and with the cylinder heads 4 by inlets 55. The pockets 53 are supplied with water through the medium of pipes 56, having communication with the water jacket 57 common to and surrounding the feeding chambers, turbines, and exhaust chambers, and supplied by a suitable top inlet means communicating with an inlet opening 58. At the lower portions of opposite ends of the motor, and communicating with the water jacket of the mixing chambers 25, are outlet pipes 59. The position of the pipes 56, or their relation to the central source of supply, is clearly illustrated by Fig. 1, and it will be understood that a continuous circulation will be maintained to keep all the parts of the motor cool, with advantages in the operation thereof and durability of the structure generally.

One of the most advantageous features of 120 the present motor organization is the construction and arrangement of the two cams 32 which control the operation of the combined valve and piston mechanism operating in conjunction with the ignition chambers 125 to not only provide means of communication between the latter chamber and pump devices and feeding chambers, but also to compress the gas entering said ignition chamber from the pumps to a considerable 130

extent previous to the ignition and explosion thereof. As clearly shown by Figs. 2 and 5, and as heretofore set forth, the edge of the cam 32 is embraced by the inner ends of the 5 entire series of plungers 33, and each cam has a large diameter 60, or a portion of the periphery thereof in concentric relation to the shaft, the said portion being precisely one half the circumferential extent of the cam. 10 At one extremity, this concentric peripheral portion 60 merges into a drop 61, which is also continuous with the lowest portion of the cam, as at 62, and this lowest portion of the cam, which is also concentric with relation to the shaft 1, continues into a slight rise 63 running into a curved portion 64, having a greater diameter than the lowest portion of the cam 62, and the said portion 64 likewise continues regularly into a straight 15 edge 65 running into the terminal of the large concentric portion of the cam opposite to the location of the drop 61.

The motor is completely enveloped in a shell or inclosure, and the parts of said shell 25 are connected by suitable bolts. As shown by Fig. 2, the blades or buckets of the turbine are carried by a hub 66 made in two pieces and held together by through-bolts 67, and other suitable bolts will be employed 30 in connecting the several chambers as well as the pump devices in operative relation. The shaft 1 is also provided with and engages thrust glands 68 to take up end play, and it is proposed to have the inner ends of these 35 glands contact with hard metal rings or wear washers 69 secured on the shaft against shoulders, as at 70, the said hard metal rings or washers 69 revolving with the shaft and obviating wear on the latter by endwise contact therewith of the inner terminals of the 40 glands.

In operation, the several pump devices have a reciprocating motion imparted to the pistons 5 through the actuation of the connecting rods 7 and 7^a when the eccentric 9 revolves. The eccentric is so positioned with respect to the pump devices that the several pistons 5 have a regular indrawing and outward forcing operation with respect 45 to the gas delivered to the mixing chambers 25, and each piston on its inward stroke, draws the gas from its mixing chamber 25 through the inlet port 24 by opening the valve 20 inwardly against the resistance of the spring 23 engaging the stem of said valve. After the piston has reached the inner limit 50 of its stroke, it immediately commences to move outwardly, allowing the valve 20 to close, and at this time the combined valve 25 and piston 36 will be in engagement with the starting point of the enlarged diametrical portion 60 of the cam 32, and the port 37 will coincide with the port 28, thus permitting 55 the gas from the pump cylinder to be forced 60 into the ignition chamber with which the

port 28 communicates, and the said ignition chamber and pump cylinder remain in communication until the stem or plunger 33 has passed over the low portion 62 of the cam and rises over the drop 61 on to the high portion or concentric elongated edge 60 of said cam, which forces the combined valve or piston outwardly and compresses the gas in the ignition chamber, and during this traverse 70 of the cam the port 38 aligns with the discharge of the ignition chamber and also with the port 45, but subsequent to the ignition of the charge of gas in the ignition chamber, and the roller 34 then traverses the inclined straight edge 65, passes over the merging 75 edge 64, and again moves down to the low portion 62. By this operation, communication between the ignition chamber and pump cylinder is shut off just prior to the explosion, and communication between the ignition chamber and feeding chamber 44 takes place immediately subsequent to the explosion, all of the exploded gas leaving the ignition chamber and passing into the receiving chamber prior to a recommunication of the 80 pump cylinder with the ignition chamber, so that there is no back pressure or frictional resistance to overcome in the pump cylinder, or disturbance of the constancy of pressure within the feeding chamber. This operation 85 will be carried on successively with the entire series of pumps and in alternation at opposite sides of the motor, and it will be understood that if the pressure becomes excessive or more gas is supplied to the mixing chamber 90 than need be utilized, the controlling valve cooperating with the supply or feed pipe for the gas will regulate the flow to the mixing chamber and thus preserve a uniformity in rotation or operation and power 95 100 of the latter.

The exhaust from the blades or buckets of the turbines at the center of the motor passes freely into the central exhaust chamber, and by this organization, together with the other 105 features of arrangement heretofore described, the end thrust of the turbine shaft is equalized.

The pumps are so arranged as to cause six 110 explosions to each revolution of the eccentric, and this will keep up a continuous pressure in the feeding chambers and, as before noted, the number of pumps may be varied in accordance with the requirements of the load.

Having thus described the invention, what is claimed is:—

1. In a gas turbine, the combination of a plurality of radially arranged pumps including piston devices, a mixing chamber common to said pumps and having communication therewith, ignition chambers also having communication with the pumps, a feeding chamber in communication with the ignition chambers, a turbine with which the 120 125 130

feeding chamber has communication, the feeding chamber being between the ignition chambers and the turbine, and automatically operating valve means in the ignition chambers having ports adapted to alternately coincide with the communicating means between the pumps and the ignition chambers and the latter and feeding chamber.

2. A gas turbine having a plurality of radially arranged pumps including piston devices, a mixing chamber having communication with the said pumps, ignition chambers also in communication with the pumps, a feeding chamber communicating with the ignition chambers, a turbine having communication with the feeding chamber, automatically operating valve means in the ignition chambers for admitting the charge of gas to the latter from the pumps, shutting off communication with the pumps, and opening communication between the ignition chambers and the feeding chamber after explosion of the charge in said ignition chambers, and a single shaft for the pumps, valve means, and turbine.

25 3. A gas turbine having a plurality of radially arranged pumps, means for supplying gas to said pump devices, a feeding chamber, ignition chambers communicating with the pumps and disposed between the feeding chamber and the pumps, the ignition chambers also having communication with the feeding chamber, automatically operating mechanism in the ignition chambers for alternately opening communication between the latter and the pump devices and the feeding chamber, a turbine device arranged adjacent to the feeding chamber and communicating with the latter, and a shaft for the turbine having the pumps and the automatically operating valve mechanism directly actuated thereby.

4. In a gas turbine, the combination of a plurality of radially arranged pumps having radially disposed piston devices and also provided with means for supplying gas thereto, a turbine shaft around which the pumps are disposed, a feeding chamber, ignition chambers between the feeding chamber and pumps and having communication with both of the latter, automatically operating mechanism directly actuated by the said shaft and disposed mainly within the ignition chambers and provided with means for alternately setting up communication between the ignition chambers and pumps and the feeding chamber, the gas being admitted from the pumps into the ignition chambers when the feeding chamber is shut off and communication between the ignition chambers and pumps being shut off just prior to the explosion and the feeding chamber open to the ignition chambers subsequent to such explosion, and a turbine for operating said shaft and with which the feeding chamber has communication.

5. In a gas turbine having a plurality of pumps with radially arranged piston devices and provided with means for supplying gas thereto, a shaft around which the said pumps are disposed and having the piston devices connected thereto, feeding chambers, a turbine arranged adjacent to and having communication with the feeding chambers and actuating the said shaft, and ignition chambers interposed between the feeding chambers and the pumps and having communication with the latter, the ignition chambers being provided with automatically operating mechanism actuated by the said shaft for admitting the gas thereto from the pumps and shutting off the pumps prior to the explosion, communication between the ignition chambers and the feeding chambers being opened subsequent to the explosion.

6. In a gas turbine, the combination with a shaft, of centrally located turbine means on the shaft for operating the latter, a plurality of radially arranged pump devices on opposite sides of the turbine means and having radially arranged piston devices connected to said shaft and provided with a gas feed, feeding mechanism adjacent to and communicating with the opposite sides of the turbine means, and ignition mechanism interposed between the feeding mechanism and the pumps and communicating with the latter and the said feeding mechanism, the ignition mechanism being provided with automatically operating mechanism directly actuated by the said shaft for alternately opening and closing the same with respect to the pumps and the feeding chambers.

7. In a gas turbine, the combination with a shaft, of turbine devices on the said shaft, a central exhaust chamber between the turbine devices and common to the latter, a plurality of concentrically arranged pumps disposed on opposite sides of the turbine devices and having radially disposed piston means connected to the shaft, feeding chambers, and ignition chambers interposed between the feeding chambers and the pumps and provided with means directly actuated by the said shaft for automatically opening and closing communication between the said feeding chambers and ignition chambers, the pumps being provided with means for supplying gas to the ignition chambers and operating on opposite sides of the turbine to continuously actuate the shaft.

8. The combination with a shaft, of a pair of turbines thereon having common exhaust means between them, pump devices arranged on the outer sides of the turbines and operating to supply the latter with a motive agent and having piston means connected to and operating in sets on the same side of the shaft and in the same axial plane in alternation to compress power fluid and rotate the said shaft, and ignition chambers interposed

between the pumps and the turbines and having piston devices connected to and operated by the said shaft and having communication with the said pumps and turbines.

- 5 9. The combination with a shaft, of turbines thereon, an exhaust chamber located between the inner portions of the turbines and common to both of the latter, means for receiving and controlling the explosion of the power 70 fluid, and concentrically arranged pump means disposed in opposite sets in operative relation to the outer portions of the turbines and having piston devices connected to and operated by the said shaft, corresponding 75 pumps of the two sets on opposite sides of the turbines on the same side of the shaft and in the same axial plane operating in alternation to compress power fluid and supply the turbines with the same fluid.
- 10 10. In a gas turbine, of the class set forth, a plurality of radially arranged pumps having radially disposed piston devices, a shaft common to all of the piston devices of the pumps, ignition chambers communicating 80 with the pumps, a feeding chamber in communication with the ignition chambers, a turbine communicating with the feeding chamber, means in the ignition chambers for automatically controlling communication 85 between the same and the pumps and the feeding chamber, and a water jacket enveloping all of the said parts and having an inlet at the upper portion of the turbine and an outlet at one end.
- 15 11. In a gas turbine, the combination of a 90 plurality of radially arranged pumps for maintaining a supply of gas, the pumps being provided with pistons having oscillating piston rods connected thereto, a shaft around which the pumps are arranged and carrying operating means for the piston rods, one of the piston rods being in the form of a holding leg which is fixed at one extremity to said operating means, mixing chambers 95 for supplying a motive agent to the said pumps, ignition chambers communicating with the pumps, and a turbine on the shaft receiving the motive agent from the ignition chambers, the turbine directly actuating the 100 shaft and through the latter also actuating the said piston rods.

- 20 12. The combination with a shaft, of two turbines thereon, an exhaust chamber located 105 between the inner portions of the turbines and common to both of the latter, pressure feeding chambers adjacent to the outer portions of and having communication with the turbines, means for controlling the supply of the pressure medium to the said feeding 110 chambers, and a plurality of concentrically arranged radially disposed pump devices having piston means arranged around and connected to the said shaft for initially regulating the supply of the pressure medium to the said controlling means.

13. The combination with a shaft, of two turbines thereon, an exhaust chamber located between the inner portions of the turbines and common to both of the latter, feeding chambers adjacent to and communicating with the outer portions of the turbines, a plurality of radially arranged pump devices arranged at opposite extremities of the complete device and having piston means connected to the shaft, and ignition chambers 75 between the pump devices and the feeding chambers, the ignition chambers communicating with the pump devices and the feeding chambers alternately at timed intervals.

14. The combination with a shaft, of a 80 turbine thereon, a feeding chamber communicating with the turbine, ignition chambers communicating with the feeding chamber, a combined valve and piston means working in the ignition chambers, and a 85 plurality of radially disposed pump devices having piston means connected to the said shaft, the combined valve and piston means working in the ignition chambers being operated by the shaft to alternately open 90 and close communication between said ignition chambers and the pump devices and the feeding chamber.

15. The combination with a shaft, of a 95 turbine thereon, a feeding chamber adjacent to and communicating with the turbine, a plurality of radially arranged pump devices having piston means co-operating with the shaft, ignition chambers having communication with the pump devices and located between the latter and the feeding chamber, and combined valve and piston means reciprocatingly mounted in the ignition chambers and having ports therein in different 100 positions for alternate registration with the communicating means between the ignition chambers and the pump devices and the receiving chamber, said valve devices operating to compress the gas in the ignition chambers prior to the explosion.

16. The combination with a shaft, of a 110 turbine thereon, a feeding chamber adjacent to and communicating with the turbine, ignition chambers in communication with the feeding chamber, outer mixing chambers, 115 pump devices having cylinders with heads communicating with the ignition chambers and the mixing chambers and also provided with valves, the pump devices being arranged around and having piston means connected to the said shaft, and an exhaust chamber located close to the inner portion of the turbine, the ignition chambers having means therein actuated by the said shaft to control the alternate communication thereof with the pump devices and the feeding chamber.

17. In a gas motor of the class set forth, the combination of a plurality of radially arranged pump devices having pistons,

means for supplying a motive agent to the pump devices and automatically controlled by the operation of the said devices, a shaft with a turbine thereon and to which the 5 pistons of the pumps are operatively connected, a feeding chamber adjacent to the turbine, ignition chambers between the feeding chamber and the pump devices, the ignition and feeding chambers and pump devices having communicating means, and reciprocating means in the ignition chambers for controlling communication between the same and the feeding chamber and pump devices, the said reciprocating means being 10 directly operated by the shaft carrying the turbine.

18. The combination with a shaft, of turbines thereon, an exhaust chamber located between the inner portions of the turbines 20 and common to both of the latter, feeding chambers adjacent to and communicating with the outer portions of the turbines, pump devices radially disposed in operative relation to the outer portions of the turbines, 25 ignition chambers between the pump devices and feeding chambers, water jackets operatively engaging the pump devices and the chambers and having communication through the entire structure thereof, a connection for supplying water to the jackets located at the upper portions of the latter, and means for withdrawing water from the 30 ends of the lower portions of the jackets.

19. The combination with a shaft, of turbines thereon, feeding chambers communicating with the outer portions of the turbines, ignition chambers having communication with the feeding chambers, an exhaust chamber between the turbines and common 35 to the latter, pump devices comprising cylinders and heads in communication with the ignition chambers, water jackets between the cylinders of the pump devices and continued into the heads, water jacket means 40 operatively engaging the chambers, pipe conduits connecting the water jackets between the cylinders and the water jacket means 45 engaging the chambers, and means for supplying and relieving the water jacket organization.

50 20. The combination with a shaft, of a turbine thereon, a feeding chamber adjacent to and communicating with the outer portion of the turbine, ignition chambers communicating with the feeding chamber, radially arranged pump devices having piston and valve means and communicating with the ignition chambers, the pistons by their operation automatically controlling the 55 in-drawing of the gas and the forcing of the gas into the ignition chambers, and mechanism operating in the ignition chambers for compressing the gas therein and automatically opening and closing communication be-

65 tween the pump devices and the ignition chambers and between the latter and the feeding chamber, the piston means of the pump devices and the mechanism operating in the ignition chambers being operatively connected to the said shaft and arranged 70 around the latter.

21. In a motor of the class set forth, the combination of turbine devices having an exhaust chamber located between the inner portions thereof and common to both, feeding chambers adjacent to and communicating with the outer portions of the turbines, a single shaft common to both turbines, and devices coöperating with the feeding chambers arranged around and actuated by the 80 said single shaft for controlling the ignition and supply of pressure medium to the turbine devices and to prevent the motive medium at the time of its ignition from passing into the feeding chambers.

85 22. The combination with a shaft, of a turbine thereon, ignition chambers, a feeding chamber between the ignition chambers and turbine, the said chambers having communication with each other, means arranged around the shaft for supplying a motive agent to the ignition chambers, a cam on the shaft, and reciprocating spring actuated valve devices radially arranged about the shaft and working in the ignition chambers 90 to alternately open and close communication between said latter elements, and the feeding chamber and the means for supplying the motive agent, the said valve devices also operating as pistons to compress the motive 100 agent in the ignition chambers prior to the ignition of said agent.

23. The combination with a shaft, of a turbine thereon, a feeding chamber communicating with the outer portion of the turbine, 105 ignition chambers having communication with the feeding chamber, means for controlling and delivering a supply of motive agent under pressure to the ignition chambers, and means in the ignition chambers for compressing the motive agent prior to the explosion thereof, and also for controlling communication between the means for supplying the motive agent and the ignition chambers, 110 and the latter elements and the feeding chamber, the said compressing and controlling means in the ignition chambers and the means for controlling the supply of motive agent under pressure being arranged around and actuated by the shaft carrying the turbine.

115 In testimony whereof I have hereunto set my hand in presence of two subscribing witnesses.

LEWIS A. HAINES.
